CLAIM

The ornamental design for an LED lamp bracket, as shown and described.

DESCRIPTION

FIG. 1 is a perspective view of an LED lamp bracket showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded view of the LED lamp bracket shown in FIG. 1.

The broken lines in the drawings depict portions of the LED lamp bracket that form no part of the claimed design.
